UNITED STATES PATENT OFFICE.

WALTER H. FLOOD, OF CHICAGO, ILLINOIS.

SPOTLIGHT-OPERATING MECHANISM.

Application filed March 11, 1922. Serial No. 542,829.

To all whom it may concern:

Be it known that I, WALTER H. FLOOD, a citizen of the United States, and a resident of the city of Chicago, in the county 5 of Cook and State of Illinois, have invented certain new and useful Improvements in a Spotlight-Operating Mechanism; and I do hereby declare that the following is a full, clear, and exact description of the same, 10 reference being had to the accompanying drawings, and to the numerals of reference marked thereon, which form a part of this specification.

This invention relates to simple control 15 means to operate an external spotlight from the interior of a car. With the ordinary spotlight or searchlight on a closed car, it is necessary to lower a window and reach outside to change the direction of the spot- 20 light.

An object of this invention is to avoid clamping the spotlight to the windshield bracket of an open car as this involves considerable annoyance when using curtains 25 with such a car as the spotlight would interfere with attaching the curtain to the windshield.

Another object is to so place the spotlight as to avoid creating a blind spot for 30 the driver. Other interiorly operated spotlights require cutting a hole in the windshield glass, which is difficult and involves danger of breakage and forms a prominent blind spot directly in the driver's field of 35 vision.

A further object is to provide positive and 40 automatic clamping means to maintain the adjustment of the spotlight against the always present vibrations and shocks incident to ordinary driving.

A further object is to so counterbalance 45 the projector as to render the operation of the light easy in any position and to thereby render it possible to make very close adjustments without delay which might be caused by moving the light past a predetermined position.

Other and further important objects of 50 this invention will be apparent from the disclosures in the drawings and specification.

The invention (in a preferred form) is 55 illustrated in the drawings and hereinafter more fully described.

On the drawings:

Figure 1 is a sectional view of the pre-

ferred form of a spotlight operating mechanism embodying this invention.

Figure 2 is a slightly enlarged section 60 along the line 2-2 of Figure 1.

Figure 2 is a slightly enlarged section 65 along the line 3-3 of Figure 1.

Figure 4 is a slightly enlarged section 70 along the line 4-4 of Figure 1.

Figure 5 is a slightly reduced fragmentary view of the spotlight connection and counterbalances.

Figure 6 is a section of a modification 75 showing electrical contacts.

As shown on the drawings:

The reference numeral 1 refers to that part 80 of the automobile used to support the spotlight. The sleeve 2 with an integral flange 3 and a loose flange 4, is rigidly attached through the support by means of screws or 85 rivets 5, according to whether the support is wood or metal. Near the outside end of the sleeve 2 are two grooves 6 and 7; the groove 6 runs completely around the sleeve, but the groove 7 is so cut as to leave a small 90 stop as shown in Figure 2. Mounted on the sleeve 2 is a sleeve 8 which is held in place by set screws 9 and is free to turn, but prevented from completely revolving by a set 95 screw 10 in the groove 7. The object of this construction is to prevent winding up the electrical conductors used in operating the spotlight. A hollow rod 11 slides in sleeves 2-8, and its outer end carries a pin 12 connected to a lug 13 on the spotlight 100 14 through the link 15. The spotlight is pivotally secured to the sleeve 8 by a pin 16. The pin 12 slides in grooves 17 in sleeve 8, whereby the spotlight turns with the sleeve 8 and has a one-direction movement 105 with regard to the sleeve. Attached to the back of the spotlight casing are counter-weights 18 to balance the casing about the pin 16. The inside end of rod 11 is tapered and holds an operating wheel 19, by means 110 of a nut 20. A locking rod 21 runs through the rod 11 and has opposed grooves 22 forming a double wedge near its outer end. Two small dogs or blocks 23 are set in these grooves and project through slots in the rod 11 to make contact with the sleeve 2. A spring 24 operates against a head 25 on the rod 21 to bring the wedge portion of rod 21 against these blocks 23, thus forcing them into firm contact with the sleeve 2 and preventing turning or sliding of the rod 11.

A modified form of a portion of this de-

- vice is shown in Figure 6, and is intended to do away with twisting of the wires to the clamp and allow complete revolution of the light. The same numerals are used for 5 similar parts shown in the other figures.
- An insulated spool 26 carrying conducting rings 27 is mounted on the sleeve 8 and turns with the same. The rings are connected to the lamp terminals by wires 28.
- 10 A stationary insulated sleeve 29 mounted on the flange 3 carries brushes 30 which make contact with the rings 27 and are connected by wires 31 through a switch to the battery or other source of electrical energy.
- 15 The operation is as follows:
- To adjust the spotlight, the head on the rod 21 is pressed inwardly thus releasing the blocks 23 from the sleeve 2. Then the wheel 19 is moved out or in to tilt the spotlight with respect to the sleeve 2 and turned either way to turn the spotlight in the same direction. By a combination of these movements, the light can be easily controlled within its range of adjustment, and releasing pressure on the head of the rod 21 at once locks this adjustment.
- It will be evident that by substituting flexible connections for rods 11 and 21, we can have a distance control for the light 30 allowing its location wherever desired, as for instance, in front of and below the top of the radiator where it will not interfere with the driver's range of vision.
- The preferred form as described above 35 is intended to be installed through the support at the front corner of the body, or through one of the pillars of a closed car.
- It will be apparent from the foregoing that this invention provides a mechanism 40 of the class described which may be economically manufactured and conveniently installed by the simple expedient of drilling a single hole through the body member.
- I am aware that many changes may be 45 made, and numerous details of construction may be varied through a wide range with- out departing from the principles of this invention, and I therefore do not purpose limiting the patent granted, otherwise than necessitated by the prior art. 50
- I claim as my invention:
1. In a spotlight, a hinged projector, a stationary sleeve attached to the vehicle, a rotatable sleeve mounted on said stationary sleeve and supporting the projector, sliding means in connection with said rotatable sleeve and said projector to cause a change in the direction of the beam of light from said projector, and automatic means within the stationary sleeve for simultaneously locking the adjustments of said projector in any position. 55
  2. In a spotlight rotatable about two axes, operating mechanism therefor, an automatic adjustment lock consisting of a spring operated wedge, dogs adapted to be separated by said wedge, and a stationary enclosing sleeve adapted to be gripped by said dogs. 60
  3. In a spotlight, a tubular member adapted for supporting the light, and expandable friction means within said tubular member for locking the same in position. 70
  4. In a spotlight, a tubular member adapted for supporting the light, expandable friction devices in said member, and longitudinally operated means in said member for expanding said friction devices. 75
  5. In an adjustable spotlight, a hollow tubular member adapted for supporting the spotlight, and coacting and relatively movable devices within said tubular member for automatically locking the spotlight at any position. 80
- In testimony whereof I have hereunto 85 subscribed my name in the presence of two subscribing witnesses.
- WALTER H. FLOOD.
